UNITED STATES PATENT OFFICE.

ASBERRY B. WALDRON, OF BRONSON, FLORIDA.

HANGER FOR SAP-GATHERING RECEPTACLES.

1,115,627.

Specification of Letters Patent.

Patented Nov. 3, 1914.

Application filed February 25, 1914. Serial No. 821,087.

To all whom it may concern:

Be it known that I, ASBERRY B. WALDRON, a citizen of the United States, residing at Bronson, in the county of Levy and State of Florida, have invented a new and useful Hanger for Sap-Gathering Receptacles; and I do hereby declare the following to be a full, clear, and exact description of the invention, such as will enable others skilled in the art to which it appertains to make and use the same.

This invention relates to the art of sap gatherers, and particularly to improvements in a hanger for the receptacle.

The aim of the invention is to form a hanger of a single piece of wire constructed to form an annular ring, with two opposite end portions of the wire twisted together to form an upstanding arm terminating in eyes, so constructed as to prevent the hanger from wabbling.

A feature of the invention is the fact that the extremities of the two end portions of the wire are twisted together to form a tongue intermediate said eyes, which extremities are also twisted partly about said arms.

In practical fields the device may be subjected to alterations, falling within the scope of what is claimed.

The invention comprises further features and combination of parts, as hereinafter set forth, shown in the drawings and claimed.

In the drawings:—Figure 1 is a view in perspective showing the improved hanger supporting the sap gathering receptacle. Fig. 2 is an enlarged detail view of the hanger. Fig. 3 is a view showing a modified form of hanger. Fig. 4 is a view showing a portion of another form of hanger.

Referring more particularly to the drawings *a* designates a tree, which may be any character. This tree has the usual gash or cut *b* to cause the gum or sap to flow from the tree. Attached in any suitable manner to the tree are the usual gutters *c* and *d*, in which the sap from the gash flows.

The hanger for supporting the sap gathering receptacle comprises a single length of wire, constructed substantially midway of its length to form a circular ring 2, adapted to receive the sap gathering receptacle or other receptacle, so that the shoulder 3 thereof will engage the ring. The portions 4 beyond this ring are twisted together as shown,

to form an upstanding arm, the extremities of which portion 4 are constructed or arranged to form eyes 6, said extremities being designated by the character 7. The parts 8 of the eyes are directed toward one another and downwardly, and in the upper outer corner bends 9, the nails or other devices 10 for supporting the handle are arranged, and by reason of the part being directed toward one another and downwardly, the hanger is prevented from wabbling. Furthermore, if the nails are arranged a trifle too close, so as to not exactly fit the corner bends, the downwardly extending parts 8 directed toward one another will wedge between the nails. The parts 11 of said extremities are twisted together to form a tongue 12, and by this twisted construction the eyes are reinforced or straightened. The parts 11 are also twisted about the arm as shown at 13.

The invention having been set forth, what is claimed as new and useful is:—

1. A sap gathering hanger formed of a single piece of wire constructed to provide a ring to receive a sap receptacle, the parts of the wire beyond the ring being twisted together to form an upstanding arm, said parts beyond the twisted portion being bent to form adjoining eyes, the extremities of said parts being twisted together to form a tongue intermediate said eyes.

2. A sap gathering hanger formed of a single piece of wire constructed to provide a ring to receive a sap receptacle, the parts of the wire beyond the ring being twisted together to form an upstanding arm, said parts beyond the twisted portion being bent to form adjoining eyes, the extremities of said parts being twisted together to form a tongue intermediate said eyes, the upper portions of the eyes being bent toward one another and downwardly to said tongue thereby forming an acute angle bend at the upper outer corners of said eyes in which nails are adapted to be arranged to support the bracket, the twisted extremities being twisted about said arm.

In testimony whereof I have signed my name to this specification in the presence of two subscribing witnesses.

ASBERRY B. WALDRON.
